FISH POLE HOLDER

Albert L. Vegors, Lehigh, Iowa

Application July 29, 1955, Serial No. 37,214

Term of patent 14 years

(Cl. D31—4)

Fig. 1 is a front perspective view of a fish pole holder showing my new design;

Fig. 2 is a side elevational view; and

Fig. 3 is a rear elevational view thereof.

I claim:

The ornamental design for a fish pole holder, substantially as shown.
